FIG. 1.

FIG. 2.

INVENTOR,

JOHN C. BOYTON.

By Hull Smith, Brock Street
Harris.

UNITED STATES PATENT OFFICE.

JOHN C. BOYTON, OF CLEVELAND, OHIO, ASSIGNOR TO THE ADAPTI COMPANY, OF CLEVELAND, OHIO, A CORPORATION OF OHIO.

DESIGN FOR AN OUTLET-BOX.

52,944.

Specification for Design.

Patented Feb. 4, 1919.

Application filed November 11, 1918. Serial No. 262,080. Term of patent 14 years.

To all whom it may concern:

Be it known that I, JOHN C. BOYTON, a citizen of the United States, residing at Cleveland, in the county of Cuyahoga and State of Ohio, have invented a new, original, and ornamental Design for Outlet-Boxes, of which the following is a specification, reference being had to the accompanying drawing, forming part hereof, wherein—

Figure 1 is a perspective view, and Fig. 2 an elevational view of the outlet box exhibiting my new design.

I claim:—

The ornamental design for an outlet box as shown.

JOHN C. BOYTON.
